CLAIM

The ornamental design for a monitor, as shown and described.

DESCRIPTION

FIG. 1 is a perspective view of a first embodiment of a monitor showing my new design;

FIG. 2 is a top plan view of the first embodiment;

FIG. 3 is a left side elevational view thereof;

FIG. 4 is a right side elevational thereof;

FIG. 5 is a front elevational view thereof;

FIG. 6 is a perspective view of a second embodiment of a monitor showing my new design;

FIG. 7 is a top plan view thereof;

FIG. 8 is a bottom plan view thereof;

FIG. 9 is a left side elevational view thereof;

FIG. 10 is a right side elevational view thereof;

FIG. 11 is a front elevational view thereof;

FIG. 12 is a rear elevational view of the first embodiment; and,

FIG. 13 is a rear elevational view of the second embodiment.

The bottom plan view of the first embodiment is the same as the bottom view as shown in FIG. 8.
